UNITED STATES PATENT OFFICE

CHARLES H. PATTEN, OF CRANSTON, RHODE ISLAND, ASSIGNOR TO GENERAL CHAIN COMPANY, A CORPORATION OF MASSACHUSETTS

FOLDABLE BRACELET BUCKLE

Application filed February 26, 1932. Serial No. 595,267.

This invention relates to a foldable bracelet buckle for use in watch bracelets and the like, for enlarging the encircling size thereof; and has for one of its objects to provide 5 a construction which may be adjusted as to size, either enlarged or decreased in size, whether the bracelet is in folded or unfolded position.

Another object of the invention is to provide a construction which may be folded to partially contract the encircling size of the bracelet and then permit the parts of the buckle to slide one on the other to further contract the encircling size of the bracelet, by 15 which a more accurate size adjustment of the bracelet may be obtained.

Another object of the invention is the provision of a folding construction of buckle by which the buckle may be moved to contracted position by a sliding of the parts when 20 in folded position and be retained in the desired adjusted position due to such contracting movement and which may be released from such retained position to slide to an expanded position without unfolding the bracelet.

Another object of the invention is the controlling of the sliding movement of the parts 30 of the buckle in movement to and from expanded position by a manually operated finger piece.

A further object of the invention is the provision of a foldable bracelet buckle with a sliding adjustment which will maintain the 35 sliding adjustment in set position even though the buckle is unfolded.

A still further object of the invention is the provision of a manually operated finger piece which although releasing the sliding parts 40 of the buckle to permit it to move to expanded position also has a stop to limit the sliding of the parts of the buckle and prevent them from becoming entirely detached.

With these and other objects in view, the invention consists of certain novel features of construction, as will be more fully described, and particularly pointed out in the appended claims.

50 In the accompanying drawing:

Fig. 1 is a perspective view of my improved buckle in contracted position.

Fig. 2 is a perspective view of the buckle in unfolded position and with the sliding part of one of the sections partially extended.

Fig. 3 is a perspective view of the channel end section.

Fig. 4 is a perspective view of the slide member movable in said channel section.

Fig. 5 is a sectional view of the channel member and showing in dotted lines the movement of the latch to released position.

Fig. 6 is a view similar to Fig. 5 with the slide member in extended position and showing the latch in released position and as forming a stop for limiting the extending movement.

Fig. 7 is a sectional view on line 7—7 of Fig. 1.

In the use of watch bracelets it is desirable to provide a buckle which in addition to folding also has slideable parts movable one on the other to accurately adjust the encircling size of the bracelet that it may fit 75 different sized arms, and I have provided for a movement which may be attained by a pushing of the sliding parts together in one direction and holding them in the position of contraction to which they are moved by means of a latch which may be engaged 80 in one of a series of catches when the sliding parts are pushed in one direction and which will remain in this adjusted position regardless of the folding or unfolding of the parts, the release of the latch and catch being controlled by the swinging of the latch 85 to a position out of the line of catches in one of the sliding parts, and which release will operate regardless of whether the buckle is in folded or unfolded position; and the following is a detailed description of the present embodiment of this invention illustrating the preferred means by which these advanced 90

advantageous results may be accomplished.

With reference to the drawing, 10 designates generally the body section which is of channel shape having a bottom wall 11, side walls 12 with inturned flanges 13. Pivotedly mounted at 14 adjacent one end of the bot- 95

100

tom wall 11 of the body section is a latch member 15 which may swing laterally of the channel section by operation of a finger piece 16 extending through the opening 17 in one of the side walls 12.

5 This latch has a resilient tongue 18 cut therefrom and bent up as at 19 to engage any one of a series of catches 20 formed in the slide member 21, which slides beneath the flanges 13 and is guided by these flanges and the side wall 12 of this channel section in its movement. This slide member consists of a plate 22 with rolled edges 23 and a series of slots 24 to form the catches 20. This 10 member 21 is also provided with an eye 25 at one end for connection of the end link 26 of the bracelet chain.

15 The end slot 27 of this series of slots is of a width greater than the width of the slots 24 so that regardless of whether the latch member is in the center position, as illustrated in Fig. 3, or at one side thereof, as 20 illustrated in Fig. 4, the bent up end 19 will engage the slot 27 and limit the relative 25 sliding movement of the parts thus forming a stop to prevent entire separation of the parts one from the other.

An intermediate section 28 is of channel shape construction to stiffen the same and 30 is hinged to the body section 10 at one end, while the other end of this intermediate section is hinged to an end section 29 which is also of channel shape and provided with side walls 30 to stiffen the same. Detents 31 35 are raised from these side walls 30 to snap beneath the edge flange 13 of the body section to hold the parts in folded position. The end section 29 is provided with an eye 32 for connection to the end link 33 of the 40 chain.

Operation

In operation the foldable section may move to or from folded position and when 45 in either folded or unfolded position the slide member 23 may be moved inwardly to contract the length of the buckle. When the latch member is in central position and the finger piece 16 pressed inwardly, as illustrated at Figs. 1 and 2, there is sufficient 50 resiliency of the tongue 18 and the catches and tongue are so shaped as to permit the upturned portion 19 to snap from one slot or catch 20 to another in the act of contracting 55 the bracelet. When, however, it is desired to expand the bracelet by a sliding movement, the finger piece is pulled outwardly to the position illustrated in Fig. 6, thus detaching the latch from the series of 60 catches and permitting such expanding movement, the parts being limited in this outward movement by the extended width of the last notch 27 with which the finger piece engages.

65 The foregoing description is directed sole-

ly towards the construction illustrated, but I desire it to be understood that I reserve the privilege of resorting to all the mechanical changes to which the device is susceptible, the invention being defined and limited only by the terms of the appended claims.

I claim:

1. A bracelet buckle comprising a plurality of sections hinged together to fold one on the other, a member slidable in one of said sections, cooperating means between said member and the section in which it is slidable for holding the parts in different positions of adjustment, said means consisting of a series of catches on one part and a separate latch pivoted on the other part, said latch and catches being relatively resiliently mounted and constructed and arranged in such a manner that said latch may be moved from one catch to another by pressure on the end of said member so as to contract the buckle, and manually operable means to control the functioning of said latch.

2. A bracelet buckle comprising a plurality of sections hinged together to fold one on the other, a member slidable in one of said sections, and cooperating means between said member and the section in which it is slidable for holding the parts in different positions of adjustment, said means consisting of a series of catches on one part and a separate latch pivoted on the other part in such manner as to swing laterally thereof, said latch and catches being relatively resiliently mounted whereby said latch may be moved from one catch to another, said latch being swingable about its pivot to remove it from the path of movement of said catches.

3. A bracelet buckle comprising a plurality of sections hinged together to fold one on the other, a member slidable in one of said sections, cooperating means between said member and the section in which it is slidable for holding the parts in different positions of adjustment, said means consisting of a series of catches on one part and a separate latch pivoted on the other part in such manner as to swing laterally thereof, said latch and catches being relatively resiliently mounted whereby said latch may be moved from one catch to another, said latch being swingable about its pivot to remove it from the path of movement of said catches, and a manually operable finger piece extending to a point outside of the section and connected to said latch for controlling the same.

4. A bracelet buckle comprising a plurality of sections hinged together, to fold one on the other, a member slidably mounted in one end section and provided with a series of spaced catches extending laterally partially the width thereof, a latch pivoted on said section and slidable over a portion of the surface of the section to and from a position to engage and disengage said catches.

5. A bracelet buckle comprising a plurality of sections hinged together to fold one on the other, a member slidably mounted in one end section and provided with a series of spaced catches extending laterally partially the width thereof, a latch pivoted on said section in such a manner as to be slidable laterally over a portion of the surface of the section to and from a position to engage and disengage said catches, and a finger piece connected to said latch to operate said latch.

10 6. A bracelet buckle comprising a plurality of sections hinged together to fold one on the other, one of said end sections being channel shaped in cross section and having side walls, a member slidable in said channel section and provided with a series of spaced catches, a separate latch pivoted on said section, and movable to and from position to engage and disengage said catches, and a finger piece connected to said latch and extending through the side wall of said channel section for moving said latch about its pivot.

15 7. A bracelet buckle comprising a plurality of sections hinged together to fold one on the other, a member slidably mounted in one end section and provided with a series of spaced catches extending laterally partially the width thereof, a latch pivoted on said section and movable to and from a position to engage said catches, and stop means to engage and disengage said latch when said latch is out of line with said catches to limit the movement of said slide member.

20 8. A foldable buckle comprising a plurality of sections hinged together to fold one on the other, a latch member pivotally mounted on one section in such a manner as to slide laterally over a portion of the surface thereof and provided with a resilient tongue, a member slidable in said tongue and provided with a plurality of slots engageable with said tongue.

25 9. A foldable buckle comprising a plurality of sections hinged together to fold one on the other, a latch member pivotally mounted on one section in such a manner as to move laterally thereof and provided with a resilient tongue, a member slidable in said section over said tongue and provided with a plurality of aligned slots extending laterally of said member engageable with said tongue and leaving an unslotted marginal edge, and means to move said tongue to slide along the unslotted marginal edge or to engage said slots.

30 10. A foldable buckle comprising a plurality of sections hinged together to fold one on the other, a latch member pivotally mounted in one section in such a manner as to move laterally thereof and provided with a resilient tongue, a member slidable in said section over said tongue and provided with a plurality of aligned slots extending laterally of said member engageable with said

tongue and leaving an unslotted marginal edge, means to move said tongue to slide along the unslotted marginal edge or to engage said slots, said means comprising a finger piece connected to said latch and extending beyond the edge of said section for the manual operation of said latch member about its pivot.

35 11. A foldable buckle comprising a plurality of sections hinged together to fold one on the other, a latch member pivotally mounted in one section in such a manner as to move laterally thereof and provided with a resilient tongue, a member slidable in said section over said tongue and provided with a plurality of aligned slots extending laterally of said member engageable with said tongue and leaving an unslotted marginal edge means to move said tongue to slide along the unslotted marginal edge or to engage said slots, a finger piece connected to said latch and extending beyond the edge of said section for the manual operation of said latch member about its pivot, and a slot at the end of said series of slots extending across said marginal edge to engage said latch and limit the movement of said slide member regardless of the position of said latch member.

In testimony whereof I affix my signature.
